DESIGN FOR A SUCTION CLEANER CASING

Clarence Karstadt, Glen Ellyn, Ill., assignor to
Birtman Electric Company, a corporation of
Illinois

Continuation of design application Serial No.
120,377, June 28, 1945, which is a continuation
of design application Serial No. 116,295, Novem-
ber 11, 1944. This application March 11, 1946,
Serial No. 127,372

Term of patent 14 years

(Cl. D9—2)

To all whom it may concern:

Be it known that I, Clarence Karstadt, a citizen
of the United States, residing at Glen Ellyn, in
the county of Du Page and State of Illinois, have
invented a new, original, and ornamental Design
for a Suction Cleaner Casing, of which the follow-
ing is a specification, reference being had to the
accompanying drawing, forming a part thereof,
in which:

Figure 1 is a side elevation of a suction cleaner
casing showing the new design; Figure 2 is a
front elevation thereof; and Figure 3 is a top plan
view.

This is a continuation of my copending applica-
tion Serial No. D. 120,377, filed June 28, 1945,

which was a continuation of application Serial
No. D. 116,295, filed November 11, 1944.

I claim

The ornamental design for a suction cleaner
casing, substantially as shown and described.

CLARENCE KARSTADT.
